UNITED STATES PATENT OFFICE.

FREDERICK R. ROBINSON, OF DETROIT, MICHIGAN, ASSIGNOR TO PACKARD MOTOR CAR COMPANY, OF DETROIT, MICHIGAN, A CORPORATION OF MICHIGAN.

CALCULATING DEVICE.

1,409,583.

Specification of Letters Patent. Patented Mar. 14, 1922.

Application filed May 1, 1920. Serial No. 378,116.

To all whom it may concern:

Be it known that I, FREDERICK R. ROBINSON, a citizen of the United States, and resident of Detroit, Wayne County, State of Michigan, have invented certain new and useful Improvements in Calculating Devices, of which the following is a specification.

This invention relates to calculating devices and more particularly to devices adapted for use in computing premiums.

There are various premium systems now in use by manufacturing concerns and in order to make clear the device to be described and claimed in this application one of these systems will be briefly described.

When a job is assigned to a workman, a certain time is allowed for completing the job and if it is completed in less than the allowed time the workman is entitled to a premium varying in amount with the time saved. Suppose for instance, a man is allowed 16 hours for a certain job and completes the job in 12 hours. He saves 4 hours or one-quarter of the time allowed, and accordingly his pay will be increased 25% for the time worked. If he is paid at the rate of 80¢ per hour he will receive for the job 80 times 12 or \$9.60 for the 12 hours worked and one quarter of \$9.60 or \$2.40 premium, making a total of \$12.00.

The premium may be computed in another way by multiplying the time worked by the time saved and dividing the result by the time allowed and this formula will give the premium hours. For the problem above stated the formula will be worked out by multiplying 12 (time worked) by 4 (time saved) and dividing the result by 16 (time allowed) giving as a result 3 premium hours. The pay for 3 premium hours at 80¢ per hour will give \$2.40 premium or the same amount as computed above. The same results as those obtained above may be obtained by logarithmic tables and such tables have been used in the device embodying my invention.

The object of the invention is to facilitate the computation of premiums under a system such as that outlined above and to enable the operator of the device to quickly and accurately determine the premium hours.

Further objects will appear as the description proceeds.

One embodiment of the invention has been illustrated in the accompanying drawings and in these drawings:

Figure 1 is an elevational view, partly in section, illustrating the calculating device in one position of adjustment of the movable members;

Figure 2 is a view, in side elevation of the device shown in Figure 1;

Figure 3 is a detail view on an enlarged scale showing the means for locking the two rotatable wheels against relative movement; and

Figure 4 is a perspective view showing a portion of the movable members rotated to a sufficient angle to enable the operator to read the result in premium hours.

In the embodiment of the invention illustrated, the calculating device comprises a base 10 and a pair of upright standards 11, the standards 11 being rigidly secured to the base and being secured to each other by means of transverse bracing rods 12. Each of the supporting standards 11 is provided with an opening 13 and in these openings are journaled shafts 14, 15 to which are fixedly secured, as by pins 16, wheels 16. Each of the wheels 16 carries on its periphery a logarithmic scale 17, the scales 17 being exactly alike on the two wheels and being disposed adjacent the inner edges of the wheels whereby they abut each other.

Means is provided for locking one of the shafts and its wheel 16 against relative movement with respect to the other shaft and wheel and this means in the particular embodiment of the invention illustrated, comprises a sleeve 18 slidably mounted on the hollow shaft 15 and having a lug 19 extending inwardly through a slot 20 in the hollow shaft 15. The lug 19 carries at its inner end a beveled locking member 21 and this member is adapted to engage a conical or beveled surface 22 formed on the shaft 14, when the sleeve 18 is moved on the hollow shaft 15.

Each of the logarithmic scales 17 carried by the wheels 16 serves two uses in the computation of the premium hours and in order to readily indicate to the operator the successive uses or functions of the scale I have provided a pair of indicators 23, 23' which are in this instance positioned adjacent the peripheries of the wheels or adjacent the

scales. The indicator 23 is fixed to the standards 11 and indicator 23' is pivotally mounted upon a pivot 24. It will be understood that both sets of indicia could be made 5 on the pivoted indicator, one on each face thereof, if desired. When the two wheels and shafts are free to rotate with respect to each other, the left hand scale (see Figure 1) represents the standard hours or time 10 allowed for a job and the right hand scale represents the elapsed hours or time consumed on a job. When these two scales have been set in a position in which the number of standard hours on the left hand scale is 15 disposed opposite the elapsed hours or time consumed on the right hand scale, the sleeve 18 is moved on the hollow shaft 15 to a position in which the locking member 21 engages the conical surface 22 on the shaft 20 14 and locks these shafts and wheels against relative movement with respect to each other. After the wheels have been so locked the two scales are utilized to indicate different units, namely gained hours for the left hand scale 25 and premium hours for the right hand scale. The indicator 23' may be moved by hand, as desired, or in order to readily indicate the change in the uses of the two scales I may provide connecting means between 30 the sleeve 18, by means of which the locking mechanism is operated, and the indicator 23'. This form of connecting means illustrated comprises a lever 24', pivoted between a pair of lugs 25 carried by one of the supporting standards 11. The lower end of the lever 24' is bifurcated and engages a channel 26 formed in the sleeve 18 and the upper end of this lever is provided with a roller 27. The roller 27 is engaged by a cam 28 35 formed on a lever 29 pivoted at 30 to one of the supporting standards 11. This lever 29 is operatively connected to the pivoted indicator 23' by a rack 31, pivoted to the lever and engaging a pinion 32 secured to 40 the indicator shaft 24. The lever 29 thus swings this indicator on its pivot as the sleeve 18 is moved into locking and unlocking position, the parts being so connected that when the sleeve 18 is in unlocking 45 50 position the indicator 23 will designate the left hand scale as standard hours and the right hand scale as elapsed hours and when the sleeve is in its locking position the indicator 23' will designate the left hand scale as gained hours and the right hand scale as premium hours. A spring 32' returns 55 lever 29 to its normal position after it has been actuated to swing the pivoted indicator and a stop 33 limits the swinging movement of the lever 29. It will be seen, therefore, that the operation of the indicator 23' is made automatic with the manipulation 60 of the locking mechanism by means of which the shafts and wheels are locked

against relative movement with respect to 65 each other. Each of the shafts, 14, 15 is provided with a handle 33' by means of which the shafts can be readily rotated to the desired position of adjustment, and the lever 29 is manipulated by a handle 34. 70

In order to make the operation of the device clear, the solution of the problem above stated in the specification will be described. Assuming that the standard time or time allowed is 16 hours, the left hand scale will 75 be set with the number 16 opposite the number 12 on the right hand scale (12 being the elapsed hours or the time worked). When the wheels have been so adjusted the sleeve 18 is moved to a position in which the two shafts and wheels are locked against relative movement with respect to each other and this movement of the sleeve also swings the indicator 23' on its pivot to a position in which the two scales are indicated 80 as gained hours and premium hours. The difference between the time allowed or 16 and the time worked or 12 being 4, this represents the gained hours and reading against 4 on the left hand scale which indicates the gained hours we find 8 on the right hand scale as indicating the premium hours. It will be seen, therefore, that the calculating device gives the same result as that obtained by means of the other two 85 methods described. 90

For convenience in illustrating the structure, the solution of another problem has been shown, since this problem does not necessitate the showing of as large a proportion of the logarithmic scale. In this problem as shown in Figure 1 the standard hours assumed is 6, the elapsed hours 3, making the gained hours 3. Referring to Figure 4 and working this problem in the 105 manner just described we note the resulting premium hours as 1, 5-10.

In the device as actually built it will be understood that the logarithmic scales run from 1 to 100, thereby giving a sufficient 110 range for the solution of any problem.

Although the scales have been illustrated as mounted upon rotatable members, it will be evident that the invention is equally well adapted to a device in which slide rules are 115 utilized, having upon them the two scales which in this instance are mounted upon the peripheries of the wheels. It will also be evident that the locking means for locking the two scales against relative movement is adapted for use in connection with such a construction and also the connection between the locking means and the indicator. 120

It will be evident to those skilled in the art that other changes and modifications in 125 the construction and in the arrangement of the cooperating parts may be made without departing from the spirit or scope of the

invention and it is my intention to cover such changes and modifications in the following claims.

What I claim and desire to secure by Letters Patent is:

1. A calculating machine comprising a pair of relatively movable members, means for locking said members against relative movement, a scale carried by each of said movable members and indicating means disposed adjacent said scales and adapted to indicate different uses for the scales in different positions of adjustment thereof. 10
2. A calculating machine comprising a pair of relatively rotatable members, means for locking said members against relative movement, a scale carried by each of said rotatable members and indicating means including an adjustable indicator disposed adjacent said scales and adapted to indicate different uses for the scales in different positions of adjustment thereof. 15
3. A calculating machine comprising a pair of relatively rotatable members, means for locking said members against relative movement, a scale carried by each of said rotatable members and indicating means including an adjustable indicator disposed adjacent said scales and adapted to indicate different uses for the scales in different positions of adjustment thereof. 20
4. A calculating machine, comprising a plurality of relatively rotatable members, means for locking said members against relative movement, a scale carried by each of said rotatable members and indicating means including an indicator disposed adjacent said scales and adapted to indicate different uses for the scales in different positions of adjustment thereof, said indicator having two sets of indicia thereon so disposed that one set is visible to the operator in each position of adjustment thereof. 25
5. A calculating machine, comprising a pair of relatively movable members, means for locking said members against relative movement, a scale carried by each of said members, a movable indicator disposed adjacent said scales, and means connected to said locking means for adjusting said indicator. 30
6. A calculating machine comprising a pair of relatively movable members, means for locking said members against relative movement, a scale carried by each of said 35
7. A calculating machine, comprising a pair of relatively rotatable members, means for locking said members against relative movement, a scale carried by each of said members and having indicia thereon, indicating means including a pivoted indicator disposed adjacent said scales and adapted to indicate different uses for said scales in different positions of adjustment thereof, and means connected to said locking means for swinging said indicator upon its pivot. 40
8. A calculating machine, comprising a pair of concentrically mounted relatively rotatable members, means locking said members against relative movement, a scale carried by each member on its periphery a movable indicator disposed adjacent said scales, and means connected to said locking means for moving said indicator. 45
9. A calculating machine comprising a base, a pair of supporting standards, a pair of shafts mounted in said standards, wheels secured to said shafts, each of said wheels having a scale on its periphery, a fixed indicator secured to said standards adjacent said wheels, an indicator pivoted adjacent the periphery of said wheels, and means for locking said wheels and shafts against relative movement with respect to each other. 50
10. A calculating machine comprising a base, a pair of supporting standards, a pair of shafts mounted in said standards, wheels secured to said shafts, each of said wheels having a scale on its periphery, an indicator pivoted adjacent the periphery of said wheels, and means for locking said wheels and shafts against relative movement with respect to each other. 55
11. A calculating machine, comprising a pair of rotatable members, means for locking said members against relative rotation, a logarithmic scale carried by the periphery of each of said members, said scales being exactly alike on the two members, indicating means adjacent the peripheries of said rotatable members, means for locking said members against relative movement, and means for adjusting said indicating means to indicate different uses for the scales. 60

In testimony whereof I affix my signature.

FREDERICK R. ROBINSON.
